UNITED STATES PATENT OFFICE.

CHARLES D. ALLAN, OF CHICAGO, ILLINOIS.

WATER-HEATER.

1,064,418.

Specification of Letters Patent. Patented June 10, 1913.

Application filed January 20, 1913. Serial No. 743,021.

To all whom it may concern:

Be it known that I, CHARLES D. ALLAN, a citizen of the United States, and a resident of Chicago, in the county of Cook and 5 State of Illinois, have invented a certain new and useful Improvement in Water-Heaters, of which the following is a specification.

This invention relates to water heaters, 10 and relates particularly to water heaters adapted for heating water both by exhaust and live steam.

In large systems of hot water heating by forced circulation, it is very desirable, for 15 reasons of economy, to utilize the exhaust steam for heating purposes to as great an extent as possible. In most cases, however, it is necessary to provide an auxiliary or live steam heater which may be used when 20 the supply of exhaust steam is inadequate, as in very cold weather, for example, or entirely lacking at such times, for example, as nights or holidays, when the main engines are not running. Heretofore, so far as I am 25 aware, the universal practice has been to employ separate exhaust and live steam heaters, which were expensive in themselves. The use of said separate heaters also necessitated separate foundations or supports and 30 separate water connections whereby the live steam heater could either be cut in or out as desired, all of which involved further expense.

The object of the present invention is to 35 provide a combined exhaust and live steam heater having a common water chamber, and so constructed and arranged that the live steam heater may be cut in or out by merely opening and closing a single valve 40 controlling the steam supply.

To this end a heater of my invention comprises the various features and details of construction hereinafter described and claimed.

45 In the accompanying drawing, in which my invention is fully illustrated—Figure 1 is a vertical central sectional view of my improved heater; and Fig. 2 is a horizontal sectional view thereof on the line 2—2 of 50 Fig. 1.

Referring now to the drawing, 1 designates the shell of my improved heater, the ends of which are adapted to be closed by means of heads 2 and 3, which are preferably secured to the ends of the shell by stud bolts and nuts or through bolts and nuts 4

5 to provide for conveniently removing said heads to provide access to the interior of the shells in case it is desired to remove any of the exhaust steam tubes, as presently described.

Secured to the shell 1 at short distances from the heads 2 and 3 are tube sheets 5 and 6, which form compartments 7 and 8 at opposite ends of the heater shell, of 65 which the chamber 7 is provided with a connection 9 adapted for connection with a source of supply of exhaust steam and the chamber 8 is provided with a connection 10 to which the exhaust steam outlet pipe is 70 adapted to be connected. Secured in the tube sheets 5 and 6 are straight tubes 11, the opposite ends of which are in open communication with the chambers 7 and 8. In the preferable construction shown, the tube 75 sheets 5 and 6 are preferably flanged at their edges, as shown at 12, and are secured to the shell 1 by means of rivets. The space 13 within the heater shell 1 between the tube sheets 5 and 6 is provided with a water inlet 14 and with a water outlet 15, which are adapted to be connected with the circulation pipes of the heating system.

Secured in and extending through the head 2 of the shell 1 and the tube sheet 5 is 85 a shell 16, the ends of which are closed by heads 17 and 18, and extending through the head 3 and the tube sheet 6 is a shell 19, the ends of which are closed by means of heads 20 and 21. The interiors of the shells 16 90 and 19 are connected by means of straight tubes 22 the opposite ends of which are secured in the heads 18 and 21 of said shells 16 and 19, respectively. The shell 16 is provided with a supply opening 23 which 95 is adapted to be connected with the source of supply of live steam and the shell 19 is provided with an opening 24 to which an exhaust pipe is adapted to be connected.

To provide adequate strength in the shells 100 16 and 19 to resist the live steam pressure to which they are subjected, the parts of said shells and their connections to other parts are preferably made by means of rivets, the heads 2 and 3 and the tube sheets 5 and 6 105 being preferably flanged around the holes therein made to receive said shells 16 and 19 to provide for conveniently riveting said shells to said heads and tube sheets.

To provide for removing the tubes 22, 110 without removing the heads 17 and 20 on the shells 16 and 19, respectively, one of the

shells, as shown, the lower shell 19, is made of a length or height slightly greater than the length of the tubes 22, while the other of said shells, as shown, the upper shell 16, is made of such length or height as to permit 5 a man to work therein conveniently in removing and expanding the tubes 22 from the tube sheet 18. To provide access to said shells 16 and 19, they are preferably provided with suitable manholes which are 10 adapted to be closed by means of manhole covers 25 and 26, which preferably open inwardly in order to better withstand the pressure in said shells 16 and 19, and said manholes being flanged inwardly to form 15 stiff rigid seats for said covers.

When it is desired to remove any of the tubes 11, this may be accomplished by removing the heads 2 and 3 of the shell 1, 20 which will expose the tube sheets 5 and 6 and the ends of said tubes 11 secured therein, which may thereupon be readily removed and replaced.

By connecting the admission opening 9 of the chamber 7 with a source of supply of 25 exhaust steam and the admission opening 23 of the shell 16 with a source of supply of live steam by means of independent pipes, it is obvious that the live steam may be 30 turned on and off quickly and conveniently and entirely independently of the supply of exhaust steam. It is also obvious that the cost of my improved heater would be materially less than the aggregate cost of the 35 separate heaters heretofore commonly used, and also that the piping will be much less complicated, and that a single foundation only will be necessary, thereby effecting all 40 of the objects of my invention.

40 I claim:—

1. A water heater comprising a shell, 45 heads which close the ends thereof, tube sheets secured in said shell at a distance from its ends and forming chambers at the ends thereof, one of said chambers being provided with an opening adapted for connection with a source of supply of exhaust steam and the other with a discharge opening, tubes which connect said chambers, opposite ends of which are secured in said 50 tube sheets; separate shells having closed ends which extend through and are secured in openings formed in the opposite ends of the heater and in the tube sheets adjacent thereto, respectively, one of said shells being provided with an opening adapted for 55 connection with a source of supply of live steam and the other with a discharge opening, tubes which connect the interiors of 60 said shells and are exposed in the space within the heater shell between the tube sheets therein, said heater shell being provided with water inlet and outlet openings which communicate with the space between said tube sheets and are 65 provided with an opening adapted for con-

ed for connection with the pipes of a heating system, substantially as described.

2. A water heater comprising a shell, heads which close the ends thereof, tube sheets secured in said shell at a distance 70 from its ends and forming chambers at the ends thereof, one of said chambers being provided with an opening adapted for connection with a source of supply of exhaust steam and the other with a discharge opening, straight tubes which connect said chambers, opposite ends of which are secured in said tube sheets, separate shells having closed ends which extend through and are secured in openings formed in the opposite 75 ends of the heater and in the tube sheets adjacent thereto, respectively, one of said shells being provided with an opening adapted for connection with a source of supply of live steam, and the other with a discharge opening, straight tubes which connect the interiors of said shells and are exposed in the space within the heater shell 80 between the tube sheets therein, said heater shell being provided with water inlet and outlet openings which communicate with the space between the tube sheets in said shell and are adapted for connection with the pipes of a heating system, substantially 85 as described.

3. A water heater comprising a shell, heads which close the ends thereof, tube sheets secured in said shell at a distance 90 from its ends and which form chambers at the ends thereof, one of said chambers being provided with an opening adapted for connection with a source of supply of exhaust steam and the other with a discharge opening, tubes which connect said chambers, the opposite ends of which are secured in said tube sheets, separate live steam shells which respectively extend through and are secured in openings formed in opposite heads of the heater and in the tube sheets adjacent thereto, respectively, and the outer ends of which, respectively, are exposed at the ends of the heater shell, one of said shells being provided with an opening adapted for connection with a source of supply of live steam and the other with a 100 discharge opening, tubes which connect the interiors of said live steam shells and are exposed in the space within the heater shell between the tube sheets therein, said heater shell being provided with water inlet and outlet openings which communicate with the space between said tube sheets and are adapted for connection with the pipes of a heating system, substantially as described.

4. A water heater comprising a shell, removable heads which close the ends thereof, tube sheets secured in said shell at a distance 105 from its ends and which form chambers at the ends thereof, one of said chambers being provided with an opening adapted for connection with a source of supply of live steam and the other with a discharge opening, tubes which connect the interiors of said live steam shells and are exposed in the space within the heater shell between the tube sheets therein, said heater shell being provided with water inlet and outlet openings which communicate with the space between said tube sheets and are adapted for connection with the pipes of a heating system, substantially as described.

110

nection with a source of supply of exhaust steam and the other with a discharge opening, straight tubes which connect said chambers, the opposite ends of which are secured 5 in said tube sheets, separate shells having ends riveted thereto which respectively extend through and are secured in openings formed in opposite heads of the heater and in the tube sheets adjacent thereto, respectively, and the outer ends of which, respectively, are exposed at the ends of the heater shell, the exposed end of one of said shells being provided with an opening adapted 10 for connection with a source of supply of live steam and the exposed end of the other of said shells being provided with a discharge opening, straight tubes the opposite ends of which are secured in the adjacent ends of said shells and which connect the interiors thereof and are exposed in the space within the heater shell between the tube

sheets therein, said heater shell being provided with water inlet and outlet openings which communicate with the space between said tube sheets and which are adapted for 25 connection with the pipes of a heating system, one of said live steam shells being slightly longer than the length of the live steam tubes and the other thereof being sufficiently long to permit a man to work therein, and said live steam shells being provided in their exposed ends with manholes and manhole covers which close said manholes, substantially as described.

In testimony that I claim the foregoing 30 as my invention, I affix my signature in the presence of two subscribing witnesses this 18th day of January, A. D., 1913.

CHARLES D. ALLAN.
